CONSTANT TENSION LETOFF MECHANISM

Carl D. Brown, Hopedale, Mass., assignor to
Draper Corporation, Hopedale, Mass., a corpora-
tion of Maine

Application November 30, 1942, Serial No. 467,331

8 Claims. (Cl. 139—108)

The present invention relates generally to improvements in let-off mechanisms for looms and, as illustrated herein, relates more particularly to the type of let-off wherein the warp beam is positively rotated to let-off warp from the warp beam.

Let-offs of the positive type usually comprise a warp beam geared to a transmitting shaft which is driven by suitable mechanism connected to the loom. The transmitting shaft is intermittently rotated and transmits the required rotary movement to the warp beam. The rate of let-off is controlled by mechanism which is responsive to the decrease in diameter of the warp on the warp beam. In order to form cloth of increased quality, the warp sheet must be maintained under an even and uniform tension and I have found that, by oscillating the warp beam during operation of the loom, such a result is easily attained.

One object of the present invention, accordingly, is to provide a loom with a positive type of let-off whereby the warp is maintained under an even and uniform tension. To this end, the let-off mechanism is provided with a warp beam which is rotatable to let-off warp, means for positively rotating the warp beam in one direction to let-off warp, and means controlled by the tension of the warp for rotating the warp beam in the opposite direction to take up warp and thus compensate for any variations in warp tension. As illustrated, the warp is maintained under a predetermined and uniform tension by a weight, which is effective through the let-off mechanism to rotate the warp beam to take up warp to compensate for any variation in warp tension.

With the above and other objects in view, the invention will now be described with particular reference to the accompanying drawing which illustrates a preferred embodiment of the invention and in which:

Fig. 1 is a view in side elevation of a portion of the left hand rear side of a loom;

Fig. 2 is a sectional view taken along line II—II of Fig. 1; and

Fig. 3 is a view in section taken along the line III—III of Fig. 1.

The illustrated embodiment of the present invention is shown herein as applied to a loom of usual construction. Only a part of the loom with the improved let-off mechanism attached thereto is shown in the drawing, the parts of the loom not shown forming no part of the present invention.

The present invention is adapted to be used with any of the so-called "positive" types of let-

off. These let-offs include a warp beam geared to a transmitting shaft which is driven from suitable mechanism connected to the loom.

For the purposes of illustration the preferred embodiment of the invention is shown as incorporating in combination with certain new parts as hereinafter described, certain other parts of a well known type of let-off. The drawing shows a portion of the rear left hand side of a loom and includes a warp beam 10 rotatably mounted in a bearing 12 fixed to the left hand side frame 14 of the loom. A similar bearing (not shown) is, of course, provided on the right hand side frame.

15 The let-off comprises a vertical worm shaft 16 rotatably mounted in spaced bearings 18, 20, and 22 formed in a bracket 24 which is pivotally mounted on the side frame 14 as will later be described. A ratchet wheel 26 is fixed to the lower end of the shaft 16 and a hand wheel 28 is fixed adjacent to the upper end thereof. The shaft 16 also has fixed thereto intermediate its ends, a worm 30.

20 The worm 30 meshes with a worm wheel 32 fixed to a horizontal shaft 34 which is rotatably mounted at one end in a bearing 36 formed in a forward extension 38 of the bracket 24 and adjacent its other end is supported in a bearing 40 fixed to the side frame 14 of the loom. The shaft 34 at its inner end carries a pinion 42 which meshes with teeth formed in a gear 44 fixed to the warp beam 10.

25 A pawl carrier 46 is loosely mounted on the worm shaft 16 and has pawls 48 and 50 mounted thereon. A rod 52 is pivotally connected to the pawl carrier 46 and is arranged to be pulled forwardly by a reciprocating link 54 to rotate the ratchet wheel 26 and the worm 30 in a direction to let-off the warp sheet from the warp beam 10. The rod 52 is returned to its original position, upon the return of the link 54, by a compression spring 56.

30 Mechanism is provided for determining the length of the forward stroke of the rod 52 which thereby determines the length of warp let-off by the warp beam 10 on each positive forward rotative movement of the pawl carrier 46. This mechanism includes a lever 58 pivoted to the left hand side frame 14 of the loom by a horizontal shaft 60 which is rotatably mounted in a bearing (not shown) suitably secured to the loom side frame 14. The lever 58 is fixed to the shaft 60 adjacent to one end thereof and the shaft intermediate its ends and outside of the loom side frame 14 has fixed thereto an upwardly

extending arm 62 pivotally connected to the lower end of a substantially vertical link 64. The upper end of the link 64 is pivotally secured to a substantially horizontal arm of a bell crank lever 66 pivoted at 68 to the loom frame 14. A lever 70 is pivoted at 72 to the loom frame. The lower end of the lever 70 embraces the rod 52 and normally engages a collar 74 fixedly secured to the rod 52.

A rod 76 is pivotally secured at one end to the top of the lever 70 and is pivotally connected at its other end to an arm 78 which is fixed to a shaft 80 mounted in a bearing 82 on a bracket 84 fixed to the side frame of the loom. A similar bracket and bearing (not shown) support the other end of the shaft 80. A whip roll 86 is mounted in a bearing 88 formed in an arm 90 fixed to the shaft 80. A compression spring 92 is mounted on the rod 76 and bears at one end against a depending arm 94 of the bell crank 66 and its other end bears against an adjusting collar 96 fixed to the rod 76. Thus, the position of the lever 70 is controlled by the diameter of the warp on the warp beam 10 and by the tension of the warp. The lower end of the lever 70 engages the collar 74 and thus determines the lost motion between the link 54 and the rod 52. As the diameter of the warp on the warp beam decreases or the tension on the warp increases the lost motion between the rod 52 and the link 54 also decreases thus providing for greater rotation of the ratchet wheel 26 to effect greater rotation of the warp beam 10 as the diameter of the warp thereon decreases or the tension on the warp increases.

As stated above, the bracket 24 is pivotally mounted for rotation about the horizontal shaft 34. Thus any tension on the warp, through the driving connections will tend to rotate the bracket 24 and the vertical worm shaft 16 and the worm 30 carried thereby in a counterclockwise direction. In order to prevent excessive rotation of the bracket 24 and also to control the tension on the warp, the bracket 24 is normally maintained in the position shown in Fig. 1 by a weight 98 slidably mounted on a horizontal arm 100 rigidly secured to and extending forwardly from the bracket 24. In order to maintain an even and uniform tension on the warp as its diameter on the warp beam 10 decreases, the position of the weight 98 is controlled by the lever 58. As shown in Fig. 1, the warp beam 10 is nearly empty and the top end of the lever 58 is in its extreme rearward position. The shaft 60, to which the lever 58 is fixed has a gear segment 102 fixed adjacent to its outer end. The gear segment 102 rotates toward the left as the diameter of the warp on the beam 10 decreases. The weight 98 is provided with teeth 104 which mesh with the teeth on the gear segment 102. Thus as the lever 58 moves inwardly toward the position shown in Fig. 1, the weight 98 also moves in the same direction toward the supporting pivot 34 on which the arm 100 and the bracket 24 are pivotally mounted.

The weight 98 is provided with a ledge 106 (Fig. 2) which is arranged to engage a shelf 108 formed on the gear segment 102 to prevent the teeth 104 on the weight 98 from damaging the teeth on the gear segment when the weight is rotated in a counter-clockwise direction during operation of the loom.

During operation of the loom, the rod 52 is moved toward the right by the link 54 and the ratchet wheel 26 and the worm shaft 16 are ro-

tated in a direction to let-off the warp. The extent of rotation of the ratchet wheel is controlled by the mechanism described above. As the loom operates and the tension on the warp increases or decreases due in part to the opening and closing of the shed, the bracket 24 and the weight 98 are rotated in clockwise and counterclockwise directions to compensate for the increased or decreased tension on the warp. As the shed closes and the tension on the warp sheet decreases, the bracket 24 and the weight 98 carried thereby will rotate in a clockwise direction and the warp beam 10 will be rotated in a direction to take up the slack and thus maintains the warp sheet under uniform tension.

The oscillation of the bracket 24 is permitted substantially independently of the pawl carrier 46. When the bracket 24 is rotated in a clockwise direction to take-up and thus compensate for any looseness in the warp, the pawl carrier 46 will rotate in a clockwise direction as viewed in Fig. 3, the rod 52 remaining stationary. This clockwise movement of the pawl carrier 46 will rotate the worm 30 and thus require that weight 98 rotate the bracket 24 very slightly farther than would be required if the worm 30 were not thus rotated. However, since rotation of the weight 98 and bracket 24 will rotate the shaft 34 through the same angle, and independent rotation of worm 30 by the pawl carrier 46 serves only to feed the worm and bracket slightly around the gear 32, the effect of this independent rotation of the worm is comparatively insignificant. When the bracket 24 is rotated in a counter-clockwise direction, the pawl carrier 46 rotates in a counter-clockwise direction and the pawls 48, 50 ride over the teeth on the ratchet wheel 26 without affecting the latter. Accordingly, the pawl carrier 46 and the pawls 48, 50 do not materially affect the oscillation of the bracket 24.

Having thus described my invention what I claim as new and desire to secure by Letters Patent of the United States is:

1. In a loom let-off, a warp beam rotatable to let-off warp, means for positively rotating the warp beam intermittently in one direction to let-off warp, means controlled by the diameter of the warp on the warp beam for varying the extent of each rotative let-off movement of the warp beam, and means controlled by said second mentioned means and by the tension of the warp for rotating the warp beam in the other direction to maintain the warp under even and uniform tension.

2. In a loom let-off, a warp beam rotatable to let-off warp, means for positively rotating the warp beam step-by-step in one direction to let-off warp, means responsive to decrease in diameter of the warp on the warp beam to increase the extent of rotation of the warp beam, and means controlled by the second mentioned means and by the tension of the warp for rotating the warp beam in the other direction to take-up slack in the warp produced during operation of the loom.

3. In a let-off for looms, a rotatable warp beam, a horizontal shaft geared to the warp beam, mechanical means actuated by a moving part of the loom for positively rotating said shaft in a direction to effect let-off of the warp beam, means controlled by the diameter of the warp on the warp beam for determining the extent of let-off rotation of said shaft, and means controlled by the tension of the warp and by said

diameter controlled means for rotating said shaft in the opposite direction to take up the warp to maintain the warp under an even and uniform tension during operation of the loom.

4. In a let-off for looms, a rotatable warp beam, a horizontal shaft geared to the warp beam, a support pivoted on said shaft, mechanical means mounted on said support for imparting a step by step rotary motion to the shaft to let off warp, automatic means for controlling the extent of step-by-step movement, means connected to said support and acting upon said shaft to rotate said shaft in the opposite direction to take up warp and connections between said last named means and said automatic means for controlling rotation of the shaft to take up warp to maintain the warp under even and uniform tension during operation of the loom.

5. In a let-off for looms, a rotatable warp beam, a horizontal shaft geared to the warp beam, a support pivoted on said shaft, mechanical means mounted on said support for imparting a step-by-step rotary motion to the shaft to let off warp, automatic means for controlling the extent of step-by-step movement, a weight slidably mounted on said support and effective to rotate said support and said shaft in the opposite direction to take up the warp, and connections between said weight and said automatic means for controlling the position of said weight on said bracket for maintaining the warp under uniform tension during operation of the loom.

6. In a let-off for looms, a rotatable warp beam, a horizontal shaft geared to the warp beam, a support pivoted on said shaft, mechanical means mounted on said support for imparting a step-by-step rotary motion to the shaft to let-off warp, automatic means for controlling the extent of step-by-step movement, a substantially horizontally extending arm fixed to said support, a weight slidably mounted on said arm arranged to rotate said support and said shaft in the opposite direction to effect take-up of the warp on the warp beam, and connections between said weight and said automatic means for sliding the weight along said arm to vary the moment of said weight directly in accordance with the varying diameter of the warp on the

warp beam to maintain the warp under uniform tension during the operation of the loom.

7. In a let-off for looms, a rotatable warp beam, a horizontal shaft geared to the warp beam, a bracket pivoted on said shaft, a vertical shaft mounted in said bracket, a ratchet wheel fixed to one end of said vertical shaft, a worm fixed to said vertical shaft intermediate its ends, a worm wheel fixed on said horizontal shaft and meshing with said worm, a pawl carrier mounted on said vertical shaft and having a pair of pawls thereon for engaging teeth on said ratchet wheel, means for rotating said pawl carrier in a direction to rotate said ratchet wheel, automatic means controlled by the diameter of the warp on the warp beam for determining the extent of rotation of said pawl carrier, a substantially horizontal arm fixed to said bracket, a weight slidably mounted on said arm, and means on said automatic means engaging said weight and positioning said weight on said arm in accordance with the varying diameter of the warp on the warp beam to maintain the warp under a uniform tension during operation of the loom.

8. In a let-off for looms, a rotatable warp beam, a horizontal shaft geared to the warp beam, a bracket pivoted on said shaft, a vertical shaft mounted in said bracket, a ratchet wheel fixed to one end of said vertical shaft, a worm fixed to said vertical shaft intermediate its ends, a worm wheel fixed on said horizontal shaft and meshing with said worm, a pawl carrier mounted on said vertical shaft and having a pair of pawls thereon for engaging teeth on said ratchet wheel, means for rotating said pawl carrier in a direction to rotate said ratchet wheel, automatic means controlled by the diameter of the warp on the warp beam for determining the extent of rotation of said pawl carrier, a substantially horizontal arm fixed to said bracket, a weight slidably mounted on said arm, said weight being effective to rotate said horizontal shaft in the opposite direction to maintain a predetermined tension on the warp, and means cooperating with said automatic means for moving said weight along said arm to maintain the warp under said predetermined tension as the diameter of the warp on the warp beam decreases.

CARL D. BROWN.
